UNITED STATES PATENT OFFICE.

PERCIVAL B. TURPIN, JR., OF TAMPA, FLORIDA.

FOOT VALVE FOR WELL CASINGS.

1,403,359.

Specification of Letters Patent. Patented Jan. 10, 1922.

Application filed March 6, 1919, Serial No. 280,900. Renewed June 7, 1921. Serial No. 475,832.

To all whom it may concern:

Be it known that I, PERCIVAL B. TURPIN, Jr., a citizen of the United States, and a resident of Tampa, in the county of Hillsborough 5 and State of Florida, have invented a new and Improved Foot Valve for Well Casings, of which the following is a full, clear, and exact description.

The present invention relates to new and 10 useful improvements in valves, and pertains more particularly to a valve adapted for use in well casings, and whereby the use of which eliminates the necessity of employing a drop pipe ordinarily necessary in well 15 construction.

The primary object of the invention is to construct a valve in such a manner that it may be removably and adjustably secured within a well casing.

20 A further object of the invention is to provide a foot valve which is capable of being positioned at any desired point in the well casing.

25 A further object of the invention is to provide a foot valve which when positioned, provides an air-tight joint between the body of the valve and the well casing, thus greatly increasing the efficiency of the valve.

30 A further object of the invention is to so construct a valve of this character that all of its several parts are readily removable and accessible for the purpose of renewal or repair.

35 Reference is to be had to the accompanying drawings forming a part of this specification in which like characters indicate corresponding parts in all the views, and in which—

40 Figure 1 is a vertical sectional view of a well casing with the foot valve inserted therein;

Fig. 2 is a similar view showing the foot valve secured in place in a well casing;

45 Fig. 3 is a transverse sectional view on the line 3—3 of Fig. 1;

Fig. 4 is a transverse sectional view on the line 4—4 of Fig. 1;

Fig. 5 is a detail view of a portion of the retaining wedge;

50 Fig. 6 is a sectional view of the tool and its centering device used in the removal of the foot valve from the casing;

Fig. 7 is a sectional view on the line 7—7 of Fig. 6;

55 Referring more particularly to the drawings, the reference character 10 designates

a well casing, which is of the ordinary construction and forms no particular part of the present invention.

Adapted to be secured within the well 60 casing 10, is a casing 11, one end of which is tapered or reduced as at 12, said reduced end 12 being provided with three equidistantly spaced slots 13, which extend throughout the reduced end 12, as shown in 65 Figures 1 and 2. The upper extremity of the reduced end 12 is provided with a screw thread 14, and threaded thereon is a ring 15 provided on its periphery with a groove 16, the purpose of which will be hereinafter 70 described.

The lower end of the casing 11 is provided with screw thread 17, and engaging with said screw thread is the screw-threaded extension 18 of a valve chamber 19. The valve 75 chamber 19 is provided with a valve seat 20, and adapted to engage said valve seat 20, is a valve 21, the valve 21 being provided with a depending stem 22, which forms means by which said valve is guided in its 80 vertical movement. Secured to the outer surface of the valve chamber 19, in equidistantly spaced relation, are spring fingers 23, which, as shown, are adapted to engage the inner surface of the well casing 10 to 85 frictionally maintain the casing 11 within the casing 10 in the operation of setting the casing 11. The casing 11 is provided near its lower end, with two parallel grooves 24, and secured within said grooves by means 90 of spring wire bands or the like, 25, is an elastic jacket 26, which though preferably formed of rubber, may be formed of any other suitable material. This jacket 26, is secured to the upper end of the casing 11, 95 by means of a spring band 27, which lies within the aforementioned groove 16.

Projecting inwardly from the casing 11, at the base of the reduced end 12, is a spider 28, the center portion of which is screw-threaded as at 29, for the reception of a suitable tool 30. Suitably mounted on the reduced end 12 of the casing 11, is a split ring 31, which is substantially wedge-shaped in cross section, and as shown in Figs. 1 and 100 2, is provided with inwardly projecting lugs 32 adapted to receive the arms 33 of a spider 34. As shown in Fig. 3, these inwardly-projecting lugs 32 are adapted to slide within the slots 13 of the reduced end 12, thus preventing rotary movement of the ring 31 with 105 respect to the reduced end 12 of the casing 110.

11. This spider 33 is provided with a screw-threaded central portion 35, which has greater internal dimensions than the screw-threaded portion 29 of the spider 28, and said screw-threaded portion 35 is adapted to receive the screw-threaded end 36 of the tool 37 shown in Fig. 5.

It will be noted that the casing 11 is of a smaller diameter than the internal diameter 10 of the well casing 10, and is freely movable longitudinally thereof except for the slight pressure exerted by the spring fingers 23.

In securing the casing 11 within the well casing 10, after the casing 11 has been properly positioned, the tool 38 is passed through the opening 35 in the spider 33 and its screw-threaded end 39 is engaged with the screw-threaded opening 29 of the spider 28. Upon rotation of the tool 38, it will be seen that the ring 31 will be moved longitudinally of the reduced end 12 of the casing 11, by reason of engagement of the shoulder 40 of the tool 38 with the top face of the body portion 34 of the spider 33. By movement of the ring 31 longitudinally of the reduced end 12 of the casing 11, said ring will be moved into the space between the casing 11 and the well casing 10, as shown in Fig. 2, forcing the elastic jacket 26 into engagement with the interior face of the well casing 10. This positioning of the parts not only serves as a means by which the casing 11 is secured within the casing 10, but also provides a water-tight joint between the casing 11 and the well casing 10, and preventing the passage of water by the casing 11, except when it enters through the space provided by the valve 21 disengaging the seat 20, which is occasioned by the operation of a suitable pumping device not forming a part of this invention.

When it is desired to remove the casing 11 from the well casing 10, the tool 37 shown in Figs. 6 and 7, is inserted into the well casing 10, and its screw-threaded end 36 is engaged with the thread 35 in the spider 34. It will now be seen that through the medium of the tool 37, the ring 31 is freely movable along the reduced end 12 of the casing 11, and out of engagement with the inner surface 50 face of the well casing 10.

This tool 37 is provided with a rigid disk 40, and secured to the upper face of said disk is a plurality of resilient fingers 41. These fingers 41 are adapted to engage the inner surface of the casing and serve to center the tool 37 in such a manner that its screw-threaded end 36 will properly engage the threads 35.

From the foregoing description, it will be apparent that the present invention provides a foot valve for well casing, which may be secured within the well casing at any desired point, and, furthermore, when the foot valve is secured within the casing, a water-

tight joint is provided and maintained between the foot valve and the well casing 10.

Having thus described the invention, what is claimed as new is—

1. A foot valve for well casings comprising a tubular body portion having a tapered end, a valve seat removably secured in the end of the body portion opposite to said tapered end, a flexible sleeve surrounding said body portion, and means interposed between the tapered end of the body portion and said flexible sleeve and movable longitudinally of said body portion for forcing the flexible sleeve into engagement with the interior of the well casing for providing an air-tight joint between said body portion and said well casing.

2. A foot valve for well casings comprising a tubular body portion having a tapered end, a valve seat removably secured in the end of the body portion opposite to said tapered end, a flexible sleeve surrounding said body portion, and an annular tapered collar surrounding the tapered end of the body portion and movable longitudinally thereof for engaging the flexible sleeve with the inner surface of the well casing for providing an air-tight joint.

3. A foot valve for well casings comprising a tubular body portion having a reduced end, a valve carrying element provided with a tapered seat removably secured in one end of said body portion, and a tapered ring embracing said reduced end of the tubular body portion and movable longitudinally thereof for securing the foot valve within a well casing.

4. A foot valve for well casings comprising a valve casing of smaller diameter than the well casing, securing means movable longitudinally of the valve casing and into engagement with the well casing for securing the valve casing in place, and means engaging the valve casing and said longitudinally movable securing means for moving the latter longitudinally of the valve casing.

5. A foot valve for well casings comprising a slotted valve casing, an annular wedge-shaped member movable longitudinally of the valve casing for engagement with the well casing, means carried by said annular wedge-shaped member and projecting through the slots in the valve casing, and means engaging the valve casing and the means carried by the wedge-shaped member and lying within the slots of the valve casing for moving the annular wedge-shaped member longitudinally of the valve casing.

6. A foot valve for well casings comprising a valve casing, an elastic covering surrounding said valve casing, and means movable longitudinally of said casing for causing engagement of the elastic covering with the well casing to retain the valve casing in place therein.

7. A foot valve for well casings comprising a valve casing, an elastic covering surrounding said valve casing, and means movable with respect to said casing for securing the valve casing in place in the well casing and maintain the elastic covering in contact with the well casing to provide an air-tight joint.
8. A foot valve for well casings comprising a valve chamber having a reduced slotted end, an annular wedge movable longitudinally of said reduced end and into engagement with the well casing for securing the valve casing in place within the well casing, means for moving the annular wedge longitudinally of said reduced end, and means for guiding said annular wedge in its movement.
9. A device of the character described comprising a valve casing, a valve seat removably secured in one end of said casing, a valve adapted for engagement with said valve seat, resilient members carried by said valve seat on the exterior thereof, an annular wedge movable longitudinally of the valve casing, and means engageable with the valve casing and with arms carried by said annular wedge for moving the latter longitudinally of the valve casing.
10. In a foot valve for well casings, a valve chamber, a pliable covering for said chamber, and means interposed between the chamber and the pliable covering for securing said valve casing within the well casing, said securing means serving in combination with the pliable covering to form a watertight joint between the well casing and the valve casing.
11. A foot valve for well casings comprising a valve casing of smaller diameter than the well casing and having a reduced end, a valve carried by the lower end of said valve casing, a pliable covering for said valve casing, a tapered ring movable longitudinally of the reduced end of said valve casing between the valve casing and the pliable covering for securing the valve casing in the well casing, and means for moving said tapered ring.

PERCIVAL B. TURPIN, JR.
